UNITED STATES PATENT OFFICE.

JACOB HOMMEL, OF LOS ANGELES, CALIFORNIA, ASSIGNOR OF ONE-HALF TO
FREDERICK T. GRIFFITH, OF SAME PLACE.

REFRIGERATOR-CAR.

SPECIFICATION forming part of Letters Patent No. 679,966, dated August 6, 1901.

Application filed September 13, 1900. Serial No. 29,956. (No model.)

To all whom it may concern:

Be it known that I, JACOB HOMMEL, a citizen of the United States, residing at Los Angeles, in the county of Los Angeles and State 5 of California, have invented new and useful Improvements in Refrigerator-Cars, of which the following is a specification.

My invention relates to means for transporting fruits, vegetables, and meats through 10 climates of variable temperature; and the object thereof is to provide a car in which a uniform temperature may be maintained for a considerable length of time, long enough to transport such articles in good condition 15 to distant markets through such variable temperature without the use of ice in such car. I accomplish this object by means of the car described herein and illustrated in the accompanying drawings, in which—

20 Figure 1 is a side view, partly in section and partly in elevation, of a car embodying my invention. Fig. 2 is a vertical section of the discharge-cocks in the bottom and top of the car. Fig. 3 is a vertical section of the 25 ventilating-valve in the top of the car. Fig. 4 is a vertical section of one of the check-valves in the partition-walls of the car.

In the drawings, A is the storing-compartment of the car, in which the articles to be 30 transported are packed, which is surrounded by two air-tight jackets or compartments B and C, which provide a receptacle for the foul air that rises or falls and separates the same from the storage-chamber where the 35 fruit or meat is stored, as will be hereinafter explained. The door of the car is likewise divided into two compartments. In each of the compartments A, B, and C are thermometers D, which register the temperature of 40 the respective compartments and are visible through glass panels E, protected by door F. Decaying fruit, meat, or vegetables will generate foul air, or gases, which will either rise to the top of the car, where it will pass from 45 compartment A through check-valve G into compartment B and thence through check-valve G' into compartment C, whence it is discharged through valve I whenever it is opened into the circulating-chamber m. If

the foul air should be heavier than the air in 50 the storage-chamber, it will fall to the bottom and pass out of the storage-chamber into the jacketing-chamber through the telescopic valve K and finally discharge from the car through the stop-cocks O.

55 The ventilating-valve I consists of a circular chamber having a valve-seat a in the top, with one port therein leading directly into the swivelly-connected pipe n, and valve-seat b in the bottom thereof, with a plurality of 60 ports. The upper and lower valve-stoppers e and f, respectively, are rigidly mounted on the valve-stem c. These valve-stoppers are provided with ports, so disposed thereon that while a port in the valve-stopper registers 65 with a port in the valve-seat the port in the other stopper does not register with the port in the adjacent valve-seat, preventing an uninterrupted flow at any time through the valve. The valve-stem is provided with a 70 crank-arm d, which is operatively connected with rod g, and that in turn is connected to crank-rod h, rigidly affixed to ventilating-funnel i. This funnel is mounted on the top 75 of the car and has a swivel-joint connection, whereby the vane j will at all times keep the mouth of the funnel to the wind. Mounted on the other end of the car and in like manner is funnel k, except that the vane is so mounted thereon as to keep the mouth of the 80 funnel away from the wind. Shifting winds will cause the funnels to rotate, which will operate the valves. This will permit the foul air in the chamber of valve I to be discharged 85 through pipe n into the ventilating-compartment m and thence out through funnel k.

In the bottom of compartment A and extending through the walls of compartments B and C is the telescopic valve K, the outer casing of which is provided with ports L, M, 90 and N, which communicate, respectively, with compartments A, B, and C. The cylindrical valve-stopper, having a rotatable motion in the outer casing, is provided with ports 1, 2, and 3, adapted when rotated to register with the ports L, M, and N, respectively, and establish communication between all of the compartments and with the outside air by means 95

of the stop-cock O. The refrigerated air is pumped into the said compartments through pipe S, which leads from the outside into these compartments. It is provided with cock T 5 for use in making outside connections.

After the car is loaded the door is sealed, so as to be air-tight. The stop-cocks O are then opened to permit the air in the car to be replaced with other air suitably prepared for 10 such purposes. Then through pipe S, I pump compartments A, B, and C full of prepared air of the required density and degree of heat or cold to keep the goods therein at the temperature desired while they are being transported to their destination to replace all the air in the car when the stop-cocks O are closed, after which more air will be pumped in to 15 give the required pressure in the storing-compartment, which will be indicated by the 20 pressure-gage R, projecting from the top of the car.

The walls of the respective compartments are preferably made of steel and are coated on both sides with a sufficient number of coats 25 of Hommel's heat-insulating paint, as described in the specification of his application for United States Letters Patent on said paint filed June 26, 1900, being Serial No. 21,677, and allowed July 31, 1900, to insulate the walls 30 to prevent the passage therethrough of heat or cold.

By my arrangement of valves it will be seen that it is immaterial whether the foul air collects at the top or settles to the bottom of the 35 car. In either case I have provided means to take the same out of the storing-chamber and finally get rid of it.

Having described my invention, what I claim as new, and desire to secure by Letters 40 Patent, is—

1. A refrigerator-car, having a main storing-chamber; air-tight chambers surrounding said storing-chamber; a thermometer in each of said chambers, valvular means to connect the said chambers together; an air-circulating chamber above said chambers; funnels revolubly mounted above and at each end of the ventilating-chamber and connecting directly with said ventilating-chamber; 45 vanes on said ventilators arranged to present the open mouth of one to the wind, and the mouth of the other from the wind, and a valve communicating with the said chambers and operatively connected with the ventilator-funnels, and adapted to be operated thereby; and a pressure-gage connected with the other jacketing-chamber.

2. In a refrigerating-car, the combination of a main storing-chamber; jacketing-chambers surrounding the storing-chamber, provided with a thermometer and pressure-gage as shown; a ventilating-chamber above the said chambers; the said chambers being valvularly connected one with the other; ventilators revolubly mounted on the car at either end thereof, the said ventilators having

vanes, as shown, and being connected with the ventilating-chamber, and provided with a bell-crank rigidly attached thereto; a rotary valve connecting the outer jacketing-chamber with the ventilating-chamber, having on the upright stem thereof, a crank; a connection-rod between the crank on the ventilator and the crank on the rotary valve, whereby the rotation of the ventilator will 75 operate the valve, substantially in the manner shown and described.

3. In a refrigerator-car, the combination of the ventilating-funnel i, rotatively mounted on the end of the car above the ventilating-chamber m and connecting directly with said chamber; the crank h attached to said ventilator; the rotary valve l connecting the ventilating-chamber with the outer jacketing-chamber C, a stem on said valve projecting therefrom and having mounted thereon a crank; the connecting-rod g, one end 80 rotatively mounted on the crank of the valve and the other end mounted on the crank on the ventilator, whereby the rotary movement 85 of the ventilator operates the valve.

4. In a refrigerator-car, having ventilating-chambers; a storing-chamber, and jacketing-chambers, as shown, the combination of the ventilating-funnel i, located at the end 90 of the car above the said ventilating-chamber and connecting directly therewith; a crank h on said ventilator; the rotary valve l, located in the partition and forming a connection between the ventilating and the outer jacketing-chambers; a crank-arm d on said valve; a connecting-rod g mounted, one end on the crank of the valve and the other end on the crank of the ventilator, substantially as 95 shown and described.

5. A refrigerator-car, comprising a storage-chamber, jacketing-chambers, surrounding the storage-chamber; valvular connections between the said chambers; a ventilating-funnel, revolubly mounted on said car 100 and carrying at its lower end a crank-arm; a rotary valve in the casing of the outer jacketing-chamber, having a crank-arm; a connecting-rod attached to said crank-arm at one end, and to the crank-arm on the ventilator to impart motion to and operate said valve when the ventilator rotates a vane on 105 said elevator to keep its mouth to the wind.

6. In a refrigerator-car, having different compartments therein, the herein-described 110 ventilating-valve l, located to give valvular connection between two different compartments, comprising a cylindrical casing, closed at the top and bottom, the same forming valve-seats for the valves, one port in the 115 upper valve-seat and a plurality of ports in the lower seat; a revoluble valve-stopper therein, having an upper member e in the top, with one port therein, and an under member with a plurality of ports; a stem c projecting 120 therefrom and having mounted thereon a crank-arm d, the said crank-arm being oper-

atively connected with a revoluble ventilator, mounted on the top of the car, and having a vane adapted to cause the ventilator to revolve when the wind shifts, substantially as 5 and for the purpose shown and described.

In witness that I claim the foregoing I have hereunto subscribed my name, this 4th day

of September, 1900, at Los Angeles, California.

JACOB HOMMEL.
